UNITED STATES PATENT OFFICE.

STANLEY NEWBOLD BARBEE, OF LOS ANGELES, CALIFORNIA.

DESIGN FOR A BOTTLE.

Application filed November 24, 1924. Serial No. 11,460. Term of patent 14 years.

To all whom it may concern:

Be it known that I, STANLEY NEWBOLD BARBEE, a citizen of the United States, residing at 1725 Whitley Ave., Los Angeles, county of Los Angeles and State of California, have invented a new and original and ornamental Design for a Bottle, of which the following is a specification, reference being had to the accompanying drawing, forming part thereof.

The figures are top, bottom, and side elevations, respectively, of a bottle showing my new design.

I claim:

The ornamental design for a bottle, as shown.

STANLEY NEWBOLD BARBEE.
